FLUSH MOUNTED TRANSDUCER SUPPORT FOR ALARM SYSTEMS

Albert L. Hermans, 3231 Roundhill Drive,
Hayward, Calif. 94542

Filed Mar. 20, 1972, Ser. No. 236,564

Term of patent 14 years

Int. Cl. D29—99; D13—03

U.S. Cl. D72—1 A

FIG_1

FIG_2

FIG_4

FIG_3

FIG_5

FIG_6

FIG. 1 is a perspective view of a flush mounted transducer support for alarm systems showing my new design; FIG. 2 is a top plan view;

FIG. 3 is an end elevational view;

FIG. 4 is a side elevational view;

FIG. 5 is a bottom plan view; and

FIG. 6 is a partial cross-sectional view taken on line 6—6 of FIG. 3.

I claim:

The ornamental design for a flush mounted transducer support for alarm systems, substantially as shown.
